DOOR OPENING AND ACTUATING
MECHANISM

Albert E. Zoller, Tiffin, Ohio

Application September 24, 1940, Serial No. 358,056

12 Claims. (Cl. 268—59)

This invention relates to mechanism for opening and closing doors and in its more specific aspects relates to a mechanism for opening and closing sectional doors of the vertical operating type.

The object of this invention is to construct a door operator in which the operating mechanism is arranged in the tracks in which the door is moved.

A further object of the invention is to construct a door operator in which the door track not only guides the door but also guides the linkage connecting the door to the operator mechanism which opens and closes the door or doors.

A further object of the invention is to construct a door operator in which an improved operating mechanism is employed and which materially reduces the number of parts employed in its assembly.

A further object of the invention is to eliminate a second track in which the door opening and closing mechanism operates and make it utilize the track in which the door is guided and travels.

A still further object of the invention is to construct a more compact door operating mechanism.

Another and further object of the invention is to construct a power actuated door operator which is self contained and which utilizes for its place of operation the usual overhead or side door track.

Another and further object of the invention is to provide a door actuating mechanism in which the door and operator are connected by a flexible linkage and in which power is applied directly to a driven jack shaft which has means for directly transmitting power to the door such that it will open and close under the influence of the applied power and not rely upon gravitational action to start the door downward during the closing operation.

Another and still further object of the invention is to provide a door mechanism which does not require the cable, chain or other lifting means extended to the base of the door which simplifies both door and guide construction.

Other and further objects of the invention will occur to those skilled in the art to which this invention appertains as the description proceeds which taken in connection with the accompanying drawings sets forth a preferred embodiment thereof as well as selected modifications. Such disclosures and descriptions are however, not to be taken as limitations of the invention which is limited only by the appended claims and any

and all variations, modifications and alterations of structure coming within the spirit and scope thereof are deemed to be included herein.

In the drawings:

5 Fig. 1 is an elevational view of my invention taken in general along the line 1—1 of Fig. 4.

Fig. 2 is a section view taken along the line 2—2 of Fig. 1.

Fig. 3 is a section view taken along the line 10 3—3 of Fig. 1.

Fig. 4 is a plan view of the operating portion of the mechanism shown in Fig. 1 with the prime mover controls added.

Fig. 5 is an elevational view of a modification 15 of the essential mechanism of the device shown in Fig. 1 with power mechanism eliminated for clarity.

Fig. 6 is a plan view of the device of Fig. 5 but with the prime mover and the controls added.

20 Fig. 7 is a view of the door operating drum employed in Fig. 5 and showing the surface construction thereof along with a schematic illustration of the door opening and closing cables.

Fig. 8 is an elevational view of the essential 25 operating mechanism of still another modification of the invention.

Fig. 9 is a modification in elevational view of a control mechanism for governing the stopping of door movement when it is being either closed or opened.

30 Fig. 10 shows a simplified circuit diagram of an appropriate motor control.

Fig. 11 shows an elevational view of the limit 35 control switch actuators which limit the door movement.

Fig. 12 shows an elevational view of a modification incorporating an extension spring counterbalance.

Fig. 13 shows a sectional detail of the base 40 mechanism employed in the power units of the several structures.

Fig. 14 shows a plan view of a detail of the structure of Fig. 12.

Door operators or door opening and closing 45 mechanism such as are commonly found in the art at the present time are either of the hand operated type or of the motor operated type. It is customary in the latter type of mechanism to install some form of circuit opening and closing device remote from the door and which may be manually operated, usually comprising a switch that must be actuated to open the door and a second switch to close the door, holding each switch until the door is either opened or 50 closed. The motor is stopped by the action of

the door or by some timing device operating in conjunction with the motor when the door is either completely opened or closed. The door operator mechanisms in the past have usually required a second track in which a traveller, carrier or other shuttle type device operates. This expedient has proven cumbersome and costly and to simplify matters the inventor has developed a means whereby the original door track is employed for the operator's shuttle or traveller which eliminates all the secondary track mechanism currently employed. The applicant applies power to a jack shaft which power is directly applied to a flexible linkage lying in the door track to thereby positively move the door to open and close same which condition does not exist in the prior art structures that rely on gravitational action to start the door around the curve of the track.

The above is embodied in a device in which 1 indicates a conventional sectional door preferably of the vertical operating type although any other type of door may be employed such as sectional doors which move horizontally. Swing-ing doors are also contemplated within the scope of the invention. A track 2 fixed to the frame work of the building structure is preferably ar-ranged in pairs in which the door rollers 3 op-erate, there being one roller for each section of the door as the preferred construction. Track 2 has a portion vertical and a portion horizontal as shown in the illustration but the essential re-quirement for sectional doors is that the tracks have two portions at approximately right angles to each other with the two portions connected by an intermediate arcuate portion. The track is generally of the sectional shape set forth in Figures 2 and 3 which is particularly adapted to keep the operator functioning in a path deter-mined by the shape of the track profile.

Means have been provided causing the door to be moved along the path determined by the elevational profile of the track. This consists initially of a motor appropriately mounted on a suitable slid-along platform in the building with which the door is associated. Integrally asso-ciated with the motor 4 is a speed reducer 5 which is operated by the motor and from which power is taken to drive the operator. Associated with the motor for controlling same is a travel mechanism or limit switch 6, more specifically detailed later in the specification, which de-termines when the motor 4 is to stop when the door is either opened or closed and 7 indicates a control box for starting, stopping and reversing the motor 4. The latter is conventional mech-anism and therefore need not be set forth in detail.

Speed reducer 5 has an ultimate shaft 8 to which are secured two sprocket gears 9 and 10. Travel mechanism 6 has a shaft 11 carrying a sprocket gear 12 which is connected to sprocket gear 10 by a chain C or other power transmitting mechanism, by means of which the travel device 6 is operated.

Mounted in the forward part of the building or structure is a shaft 13 which carries three sprocket gears 14, 15 and 16. Sprocket gear 15 is in line with sprocket gear 9 and is connected thereto by means of a chain 17 or other power transmitting mechanism. Concentrically mount-ed on the shaft 13 and schematically represented is a spiral counterbalancing spring 18. Shaft 13 is journalled in a plurality of bearing brackets 19 secured to a portion of the building struc-

ture. One end of the spring 18 is stationarily fixed to one of the brackets 19 by a screw 20 secured into collar 20' fixed to a bracket 19 and the other end of the spring is secured to a collar 21 carried by shaft 13. Spiral spring 18 func-tions as a counter-balance for the door 1 as will be hereinafter more specifically set forth.

At the rear end of the track 2, on a support 2a is mounted a pulley or sprocket gear 22 which is rotatably disposed in a pulley block 23 having an extension 23a slidably disposed in a bracket 24 fixed to support 2a. A tensioning spring 25 is concentrically mounted on extension 23a, and retained thereon by a conventional pin and washer device. The spring keeps chain or other power transmitting mechanism connecting sprocket 15 and sprocket 22 taut.

Supported in and on the track 2 is a traveling block, traveller or shuttle 27 which is provided with a pair of lugs 28 to which each end of the chain 26 is appropriately connected by con-nectors 28a and 28b, as particularly shown in Figures 1 and 4. Each track 2 is provided with a similar chain and traveling block and tensioned sprocket gears 22 as illustrated.

Each traveling block or traveller 27 is directly connected to the door 1 by means of a linkage mechanism 29 comprising a series of links 30 which are connected together by means of a series of pins 31. Each pin 31 carries a roller 32 which travels in track 2 in the manner shown in Figure 2. The roller 32 is of such a size as will substantially fill the space provided there-fore in track 2. A link 33 is connected to a pin 34 carried by a bracket 35 mounted on the door 1 and pin 34 may have a door roller 3 associated therewith operating in the track 2. As previously indicated each section of the door 1 is provided with a bracket or pair of brackets 36 rotatably supporting rollers 3 in the track 2. The door is provided with rollers 3 at each end thereof to simplify the operation thereof and to facilitate the raising and lowering or rather the opening and closing of the door with a minimum of effort.

The operation of this device is effected by the reciproca-tion of traveling block 27 actuated by power supplied by the motor 4. The linkage 29 and all succeeding door rollers 3 follow the profile of the track 2 and enable the opening and the closing of the door by tension applied di-rectly to the door through the linkage 29 and associated rollers 32 carried thereby such that auxiliary mechanisms previously supplied have been eliminated. Assuming therefore that the door is in a closed position spring 18 will be in a tensioned condition.

When traveller 27 moves to the left as observed in Figure 1 it will draw door 1 upward with it and at the same time begin to unwind the spring 18 which counter-balances the door 1. When the door is in the open position travel mechanism 6 will stop the motor. Reversely when the door closes spring 20 will wind to counter-balance the door and when closed timing mechanism 6 will again stop motor 4. The support 2a carries a safety switch 37 on it which will stop motor 4 when there is an excessive load beyond that required to open and close the door. Extension 23a carries a bracket 23b which is spring connected to switch 37.

Figures 5 and 6 set forth a modification of the operator for opening and closing door 38. A track 39 similar in profile to track 2 support a traveler 40 which is connected to door 38 by means of a linkage 41 that is provided with a plu-

rality of link bars 42 connected together by means of pins 43 which rotatably support rollers 44 moving in track 39. The linkage 41 draws the door through its track upon motion thereof to the right or to the left to open and close the same such that the door rollers 45 travel in the same path as rollers 44.

Traveler 40 is actuated from a motor, travel and control mechanism 4', 6' and 7' as previously described. The power mechanism is equipped with a speed reducer 5' which is provided with an ultimate shaft 8' carrying a sprocket gear 46 which is operatively connected to a sprocket gear 47 by means of a chain 48. Sprocket 47 is secured to a shaft 49 which is rotatably supported in appropriate bearings 50 and which has mounted thereon a pair of drums 51. Each drum 51 as particularly shown in Figure 7 is spirally grooved or scored as indicated at 52. Mounted at the right hand end of track 39 is a bracket 53 rotatably supporting roller or sheave 54 and affixed to a portion of the building wall 55 is a second bracket 56 rotatably supporting a sheave or pulley wheel 57. A cable 58 is secured at its one end to traveler 40 and passes around sheave 57 thence to sheave 54 and is then led to drum 51 and secured thereto. A second cable 59 is connected to the traveler 40 and follows the horizontal portion of the track 39 thence to the drum and is secured thereto. The general idea of the two cables 58 and 59 and their mode of securing to the drum 51 is such that one of the cables will be wound on the drum 51 as the other is unwound to thereby move the traveler 40 back and forth in the track 39 to thereby raise and lower the door 38. Slippage of the cable on the drums 51 is prevented by reason of the fact that they are grooved as illustrated in Figure 7.

Means have been provided to counter-balance the weight of the door 38, and to this end a second shaft 60 is disposed in a substantially parallel relation to shaft 49 which is suitably mounted in hanger bearings 61. Fixedly disposed on the shaft 60 are a pair of drums 62 which may be grooved in a manner similar to drum 51 as illustrated in Figure 7. Cables 63 are affixed to drums 51 and extend to and are wound around drums 62 in such a manner that the cables 63 are substantially unwound from drums 62 when the door is in its closed position. The counter-balancing is effected by a spiral spring 64 wound around shaft 60 and which has its one end secured to the shaft 60 at 65 and the other end of the spring is secured to a secondary hanger bearing 66 at 67. The spring 64 is disposed between a fixed and a relatively movable part of the mechanism to effect the counter-balancing; the spring being in a taut condition when the door is down or closed and in a relaxed condition when it is up.

A further modification of the door operator is set forth in Figure 8 which shows a door 68 actuated by a traveler 69 moving in a track 70. The traveler 69 is connected to the door 68 by linkage mechanism 92 identical with that previously described. The traveler 69 is reciprocated in the track 70 by means of an elongated screw member 71 arranged as shown in Figure 8. The shaft is journaled in a bearing 72 carried by the track 70 and its opposite end is journaled in a bearing 73 secured to a portion of the structure with which the door is associated. The shaft 71 is rotated by means of a motor 74 which is connected thereto by a gear train 75. The second track (not shown) in this disclosure is operated by means of a similar mechanism and supplied from the motor 74, gear 75' indicating the start

of a second gear train. It will be understood that the proper gear reduction and rotational relationship between the shaft (not shown) and shaft 71 will be established such that the proper movement will be given to the traveler 69 and its complementary traveler (not shown). The motor is controlled by a means similar to that shown in Figure 4. A counter-balance is intended to be used in connection with this operator and may be similar to any illustrated.

A modified form of motor control to stop the motor at the extreme limits of travel of the door is shown in Figure 9. Track 80 has a traveller 81 arranged thereon adapted to be reciprocated on the track by means of cable or chain 82 and 83. Disposed in parallel relation to track 80 is a rod 84 on which two stop members 85 and 86 are mounted. The stop members 85 and 86 are rigidly secured on said rod and brackets 87 and 88 may be arranged on track 80 to guide rod 84. A switch 88, having a lever or actuator 89, is arranged, at the end of track 80 and when traveller 81 engages either of stops 85 or 86 the rod 84 is reciprocated until pin 90 throws switch lever 89 from side to side to stop the motor. Chain 82 is placed about a pulley 82a, arranged in a block 82b slidably disposed in support 80a and is tensioned by device 80c. A safety switch 37' functions similarly to switch 37.

A safety mechanism is provided to stop motor 4' in the event the power unit is working against an overload. This comprises an arm 101 spring connected to safety toggle switch 102. This switch is actuated when the distance between arm 101, adjacent limit switch 6 supported on slidable frame 106a and also mounting the power unit and the speed reducer 5, is increased whereupon the switch 102 will be actuated. The frame 106a, supporting elements 4, 5 and 6, is capable of moving in frame 106. Studs 104 are fixed in and to the slidable frame 106a and springs 103 are carried on them and act against fixed frame 106 fixedly mounted in the building. The relative movement is against springs 103 and they are tensioned to determine the point at which switch 102 will operate to stop motor 4. This arrangement is intended to be provided in the other forms of the invention although not shown specifically in each form.

Figure 10 illustrates a simple motor starting system and is operable by two push button controls 111 and 112, one to open and one to close the door. Motor 4 is shown with the conventional field and armature connected through a switch 107 to incoming lines 108. Connected in the circuit are the limit switches 109 and 110 which are adapted to stop the motor 4 when the door is at either extreme limit of travel, i. e., either open or closed. These switches operate without regard to push button controls 111 or 112. Safety switches are also shown in the line to show that they will stop motor 4 on excessive overloads.

Figure 11 shows the construction and operation of travel switch or limiting mechanism 6. The numerals applied to the basic structure in Figs. 1 and 4 are applied herein. The shaft 11 is rotatably supported in the housing 113 and is threaded over its entire length as shown. A pair of adjustable switch actuators 114 and 115 are mounted on a carrier 116 having a guide 117 operating in a slot (not shown) to prevent movable carrier 116 from rotating on shaft 11 as it is driven by motor 4. Since motor 4 is reversible it is evident that shaft 11 is likewise reversible and therefore actuators 114 and 115 are adapted to open

switches 109 and 110 when door 1 has been opened or closed. Actuators 114 and 115 are adjustably set on shaft 118 such that the open and closed position of door 1 will coincide with the time when either of the actuators open either of the switches 109 and 110 by being moved from one end of the shaft 11 to the other end thereof.

A modified counterbalance is shown in Figs. 12 and 14. A traveller 119 slidably mounted in track 130 is link connected to a door 120 by a link means previously described. A power driven shaft 125 is provided, corresponding to shaft 49 carrying drums 51, and carries a drum 126. The door 120 is opened by cable 127 attached to the traveller 119 and is secured to and led over drum 126. To close the door a second cable 132 is provided that is connected to traveller 119, led around sheave 133, rotatably mounted in frame 134 secured to the building, and thence over sheave 131 rotatably mounted on the end of track 130, and thence over drum 126 to which it is connected. A third cable is fixed to bracket 129, secured to track 130, and led around sheave 122, rotatably mounted in frame 123 and thence connected to drum 126. The door is counterbalanced by spring 121 connected between sheave frame 123 and a bracket 124 fixed to the frame of the building. Units 4, 5, 6 and 7 may be employed to drive shaft 125 whereby drum 126 will wind and unwind the cables to positively open and close the door 120. This type of counterbalance can be easily adapted to any of the other forms of operators shown by merely connecting it between the traveler and the building. In so doing the secondary shaft and drum in Figures 5 and 6 could be eliminated and the mechanism of Figures 1-4 would have the spiral spring removed from shaft 13. Each of these mechanisms are deemed the full equivalent of the other. The choice of use is dependent upon the particular application of the door operator.

That which is considered new, novel and useful and which is sought to be protected by Letters Patent of the United States is as follows:

1. In a door operating mechanism; a track, said track having two portions at approximately right angles to each other, and said portions connected by an arcuate portion; a door slidably mounted relative to said track; a single traveler means reciprocably mounted in said tracks to open and close said door; a single flexible linkage means connecting said traveler means and said door; said linkage means operating within said track to draw said door through said arcuate portion and a reversible power mechanism connected to said traveler and adapted to reciprocate said traveler along said track to open and close said door.

2. A door operating mechanism; a sectional door; a track in which said door is slidably mounted, said track having two portions substantially at right angles to each other and connected by an arcuate portion; a single reciprocating traveler means carried by said track to move said door relative to said track to open and close said door; means connecting said door and said reciprocating traveler means, said means comprising a single system of links so constructed and arranged as to operate in said track and which lie in the bend of said track when said door is closed and a reversible power means to reciprocate said reciprocating traveler means said power means applied directly to said traveler means.

3. In a door operating means; a sectional door; 75

a track in which said door operates; a single traveler carried by said track; a single push-pull linkage connecting said traveler and said door; means carried by said linkage operating in said tracks to enable said linkage to transmit force applied to said traveler along said track to said door to open and close same and a reversible power means connected to said single traveler to open and close said door.

4. In a door operator; a track having a portion vertically disposed and one portion substantially horizontally disposed; means to move a door from the vertical to the horizontal plane and vice versa; said means including a traveller mounted in said track, a sprocket mounted on said track, a shaft rotatably mounted above said track and supporting a sprocket, a motor operatively connected to said shaft; a chain passing around said sprockets, each end of which is connected to said traveller and a counter-balancing spring on said shaft to counter-balance the weight of said door; a flexible linkage connected to said traveller at its one end and connectible to a door at its other end, and said linkage having roller means thereon to operate in said track such that force applied to said traveller will be directly applied to said linkage substantially parallel to said track.

5. In a door opening and closing mechanism for a building; a pair of tracks having one portion lying in a plane at an angle to another portion of the tracks; means to move said door relative to said tracks, including a traveller on each of said tracks, a motor, a shaft supporting a pair of drums, a pair of sheaves and operatively associated with said motor, one on said track and the other on said building, a pair of cables for each track, one of which connects from each of said travellers to each of said drums and the other of which leads from said traveller over each of said sheaves to said drums, a second shaft parallel to said first shaft carrying a pair of drums, cables connecting each of said second pairs of drums with said first pair, and a spiral counter-balancing spring connected to said second shaft to counter-balance said door; track supported linkage means connecting said door and said travellers, said linkage means adapted to cause said linkage to follow the path of said door tracks when opening and closing said door.

6. In a door operator; a track lying in two planes, said track planes connected by a bent portion; a traveller movable in one plane of said track; a single linkage connectible to said traveller; a prime mover; a jack shaft driven by said prime mover; wheels mounted near one end of said track; power transmitting means connected to said traveler and led around said wheels and jack shaft; said traveler moving said linkage substantially axially of said track; means to control the stopping and starting of said motor; and means to stop said motor upon over loading said power transmitting means.

7. In a door operator; a track having two portions disposed at substantially right angles to each other connected by an arcuate portion; a single traveler means reciprocably mounted in said track; a single roller supported linkage system connected to said traveler at its one end and lying in said track and connectible to a door at its other end; and a reversible power operated mechanism connected to said traveler to draw said linkage and the door connected thereto around the arcuate portion.

8. In a closure operator; a track having two

portions disposed substantially at right angles to each other, said portions connected by an arcuate portion; a single reciprocating traveler means supported in said track; a linkage connected to said traveler at its one end and connectable at its other end to the closure disposed externally of said track and supported by rollers operating in said track; said linkage lying about said arcuate portion of said track when said closure is in the closed position; a reversible power means for reciprocating said traveler and means connecting said power means and said traveler such that power will be directly selectively applied to both ends of said traveler to reciprocate said linkage in said track.

9. In a door operator; a track having a portion horizontally and a portion vertically disposed connected by an arcuate portion; a traveler arranged in said track operable in a single plane thereof; a linkage connected to said traveler and supported by rollers operating in said track; means to reciprocate said traveler and linkage along said track, which comprises a rotatable means supported adjacent one end of said shaft; a motor driven shaft; power transmitting means connecting said shafts and connected to the ends of said traveler; a counterbalance associated with said shaft; and a motor operatively connected to said power driven shaft; said linkage and traveler directing the force applied thereto axially of said track.

10. In a door operator; a track; a traveler in said track; means to move said traveler in said track in a single plane thereof, which includes; a motor; a shaft driven by said motor; a second shaft mounted adjacent the end of the track, wheel elements on each of said shafts and power transmitting means above each of said shafts and connected to opposite ends of said traveler; a

flexible linkage disposed adjacent said track and rollers mounted in said linkage and operatively disposed on said track, said linkage connectible to a door; and said traveler moving said linkage axially of said track.

11. In a door operator; a track having two angularly disposed portions; a traveler on said track operable in one of said portions; a linkage connected to said traveler and connectible to a door, said linkage having rollers supported thereon operatively disposed in said track; a prime mover; a shaft driven by said prime mover and having a wheel thereon; a wheel mounted for rotation adjacent one end of said track; a power transmitting means disposed about said wheels and connected to opposite ends of said traveler; and said traveler moving said roller mounted linkage axially of said track in any plane thereof.
12. In a door operator; a pair of track elements each of which has portions lying in different planes; a traveler mounted in each track operable in one of said planes; a flexible linkage connected to each traveler and disposed adjacent said track; rollers fixed to said linkage and rollable on said tracks; said linkage connected to said traveler and also connectible to a door; a prime mover; a shaft driven by said prime mover; pulleys on said shaft, one disposed adjacent each track; pulleys supported for rotation adjacent the end of one portion of each of said tracks; power transmitting elements associated with said pulleys and having the ends thereof connected to opposite ends of each of said travelers; and said travelers reciprocated along said track by said prime mover and moving said linkage as well as a door connected thereto axially of said tracks.

ALBERT E. ZOLLER.
